U.S. Appl. No. 29/637,724, filed Feb. 21, 2018, Hadley

Primary Examiner — Cynthia M. Chin*(74) Attorney, Agent, or Firm* — Knobbe Martens Olson & Bear, LLP(57) **CLAIM**

The ornamental design for an electric scooter, as shown and described.

DESCRIPTION

FIG. 1 is a perspective view showing a top surface of an electric scooter;

FIG. 2 is a front view thereof;

FIG. 3 is a rear view thereof;

FIG. 4 is a left side view thereof;

FIG. 5 is a right side view thereof;

FIG. 6 is a top view thereof; and,

FIG. 7 is a bottom view thereof.

Broken lines are used to illustrate portions of the electric scooter which form no part of the claimed design.
